UNITED STATES PATENT OFFICE.

ARCHIBALD S. FULLER, OF NEWTON, MASSACHUSETTS.

COMBING-MACHINE.

1,214,533.

Specification of Letters Patent.

Patented Feb. 6, 1917.

Application filed April 16, 1915. Serial No. 21,676.

To all whom it may concern:

Be it known that I, ARCHIBALD S. FULLER, a subject of the King of Great Britain, and resident of Newton, in the county of Middlesex and State of Massachusetts, have invented new and useful Improvements in Combing-Machines, of which the following is a specification.

This invention relates to a combing machine of the character shown in Letters Patent of the United States to J. W. Nasmith No. 724,119, dated March 31, 1903, and consists in certain improvements upon and modification of said Nasmith patent. The machine as a whole, in its general purpose, construction and mode of operation, may be substantially similar to that shown in said Nasmith patent and in the machines heretofore manufactured thereunder, and will be readily understood by those skilled in the art without any detailed description of the general features of the machine. Reference is therefore made to the well known machines made in accordance with said Nasmith patent for a general description of said machine, and the present specification will be addressed particularly to the novel features which constitute the subject matter of the present invention.

Referring to the accompanying drawings, which illustrate one embodiment of the invention,—Figure 1 is a side elevation, partly in vertical section, of such parts of a combing machine embodying the invention as are necessary for an understanding of the invention; Figs. 2, 3 and 4 are similar views illustrating different positions of the nipper; Fig. 5 is an enlarged detail view, partly in side elevation and partly in section, of the nipper and certain associated parts; Fig. 6 is a view, partly broken away and partly in section on line 6—6 of Fig. 4, showing a rear elevation of the nipper bridge or carriage; Fig. 6^a is a sectional detail on line 6^a—6^a of Fig. 6; and Fig. 7 is a plan view of the machine on an enlarged scale, parts being broken away.

The nipper shaft 1 is a rock shaft, which is rocked to and fro by a crank (not shown). Arms 2 are rigidly fixed to shaft 1 to swing therewith, and are connected to the nipper carrying arms 3, one of which is pivotally mounted at each side of each head of the machine on a stud 4 on the machine frame. The arms 3 are connected to and oscillated by rock shaft 1 and arms 2 through con-

necting rods 5 and yokes 5^a, of which there are two, each pivotally connected at one end to one of the arms 2, and at the other end to a stud 6. Each stud 6 is secured to a bracket 7 which is fixed to arm 3. Rods 5 and yokes 5^a are joined by adjusting nuts 8.

The nipper consists of the upper nipper jaw or nipper knife 9, and the lower nipper jaw or cushion plate 10. The upper nipper jaw 9 is fixed to a pair of lever arms 11 which are journaled to swing on studs 6. The rear ends of said arms 11 are connected by a cross bar or shaft 12, carrying a bowl 13, which contacts with cam surfaces hereafter described, governing the path of movement of the nipper jaws. A light tension spring 14 normally tends to urge the rear ends of said arms 11 upward, and consequently said jaw 9 downward.

The lower nipper jaw 10 is fixed to a bridge piece or support 16, which is journaled by knuckles 17 on stud 6. Said support 16 has a shelf extending in an approximately horizontal or lateral plane, to which the jaw plate 10 is screwed or bolted, and a depending flange or web, provided with arms 18 to which tension springs 19 are attached at one end. Said springs are attached at the other end to arms 3 by suitable studs, 85 and tend to urge the shelf or support 16 and the lower jaw plate 10 upward toward the upper jaw plate 9. The upward movement of the jaw plate 10 is limited by the adjustable screws 20 which pass through suitable holes in the jaw plate 10, and are screwed into brackets 21 fixed to arms 3. When the top nipper jaw 9 is raised or opened the support 16 and nipper jaw 10 are pulled upward by springs 19 until stopped by the heads of screws 20. When the nipper closes, the lower jaw 10 is depressed by the top jaw 9, away from the heads of screws 20, and the springs 19 urge the lower jaw 10 upward with a yielding pressure against the top jaw 9. The space in which jaw 10 is allowed to play between the heads of screws 20 and the brackets 21 is sufficient to allow for the required movement of the lower jaw under the control of the upper jaw in the manner hereinafter described, and also to allow for any required thickness of cotton held between the jaws.

During the movement of the nipper forward and backward by the rock shaft 1, the path of the movement is governed or controlled by the control of the top jaw by means

of the control plate or cam 22 and the nipper opening cam 23, which engage the bowl or roller 13 on arm 11 at the under and upper sides respectively of said roller. The control cams 22 and 23 are secured to the frame of the machine, and are adjustable up and down by means of adjusting screws or bolts 24 and 25. The tension of springs 19 is sufficient to overcome the tension of spring 14 so that when the bowl or roller 13 is out of engagement with cam 23 the lower jaw 10 will hold the upper jaw 9 upward and the roller 13 downward in engagement with the control cam surface 22.

15 Heretofore in the well known combers of this type exemplified by said Nasmith Patent No. 724,119 the lower nipper jaw has been fixed on the nipper carrying frame or arms 3, and has therefore governed the path 20 of the nipper in its movement forward and backward over the combing cylinder 26; and inasmuch as the nipper is thereby caused to move in the arc of a circle about the pivot 4 as a center, while the needles 27 of the combing cylinder 26 revolve in the arc of a much 25 smaller circle centered at 28, the nipper jaws are nearer the combing needles 27 when in a straight line passing through both centers 4 and 28, than in the parts of their paths at 30 the front or rear of said straight line.

In the present invention the path of the nipper jaws and consequently the position of the nipper jaws relative to the combing needles at all points in the path of the nipper jaws, is governed not by the lower jaw in fixed position on the arms 3, but by the upper jaw which is movable on arms 3. The path of movement of the upper jaw, and consequently of the lower jaw, during 40 the oscillations of the arms 3, is controlled while the jaws are closed, by the cam or guide-way 22. The guide surface of cam 22 is so shaped that during the time the nipper swings over the cylinder needles the 45 distance between the lower edge of the nipper knife 9 and the points of the needles is maintained uniform, or is varied, as desired. The path of the nipper jaws is not limited as heretofore to the arc of a circle about 4 as 50 a center. The path of the nipper jaws may be made to follow the arc of a circle concentric with the combing cylinder, in which case the nipper jaws will be at all points in their path the same distance from the 55 needle points; or the path may be varied to secure any desired result. This is accomplished by making the guideway or cam 22 of the desired shape. Good results will be obtained by making the cam 22 of such 60 shape as to cause the lower edge of the nipper jaw 9 to follow the arc of a true circle close to and parallel to the points of the needles. It is recommended however that the cam 22 be so shaped as to bring the path 65 of the nipper jaws a little nearer the needles

when the front or leading rows of needles are first entering the lap of fibers held by the nipple. The leading needles are the coarsest and a more perfect penetration of the lap of cotton by the coarser needles first 70 entering it is insured by having the lap held closest to the needles when the combing operation begins. As a result of such complete penetration of the lap there will be less breaking of the fibers, and webs of better 75 quality will be produced with less waste. As the combing progresses the path of the 80 nipper jaws may diverge a little from the needles as the finer needles will penetrate more readily because the lap will have been 85 partially combed out by the coarser needles.

It will be noticed that as the end of the upper jaw overlaps the end of the lower jaw, it is the extreme lower end or edge of the upper jaw which determines how close 85 the lap is held to the needles. In former machines of this character where the lower jaw was in fixed position on arms 3, if a lap thicker than usual were used it would tend to raise the upper jaw thus varying 90 the distance of the lower and determining edge of the upper jaw from the needles. This sometimes prevented good penetration 95 of the needles and introduced a variable condition dependent on the thickness of the lap being treated. In the present invention the upper nipper jaw is positively controlled and follows the same path for which it is set quite irrespective of the thickness of the lap or tuft of cotton projecting from between the jaws. When the nipper is closed 100 the lower jaw 10 acting as a cushion plate is pressed downward, against the tension of springs 19, sufficient downward movement of the jaw 10 being provided for to allow 105 any required thickness of cotton to be held between the jaws, and to allow the lower jaw to follow the positively controlled path of the upper jaw 9 against which it is 110 urged by springs 19.

To explain one cycle of operations: Starting with the position shown in Fig. 4, the nipper jaws have just closed upon a tuft of cotton and are moving rearwardly, or to the left as viewed in the drawings, and 115 the leading and coarser rows of needles 27 on the combing cylinder 26, are just approaching and about to penetrate the tuft projecting from between the nipper jaws. It will be understood that the combing cylinder is rotating continuously in the direction of the arrow. As the foremost rows of needles pierce and comb through the tuft, the nipper continues to move backward, its path being governed by the shape of cam 120 surface 22, until in Fig. 1, which represents the next position, somewhat more than half of the rows of needles have passed through the tuft, and the nipper is approaching its 125 extreme rearward position.

Fig. 2, representing the next stage, shows the nipper at its extreme rearward position and about to start forward, with only a few rows of the finer needles remaining to 5 pass through the tuft. From that position the nipper moves forward in the same direction as the combing cylinder but at a little slower speed, so that the last few rows of the finer needles pass through the tuft comparatively slowly, thus preventing injury 10 to the fibers. The path of the closed nipper is at all times controlled by cam surface 22 and is made to follow the path of the needles at such predetermined distance or 15 distances as may be desired. When the needles pass clear of the tuft the roller 13 engages cam surface 23 and the upper nipper jaw starts to open. The opening nipper continues its forward movement and the tuft 20 is seized by the detaching rollers 29, the action of which is essentially the same as described in said Nasmith patent.

Fig. 3 shows the nipper in its extreme forward position with the nipper jaws wide 25 open, at which time the cylinder 26 will have turned so that the needles are in the position shown. Thereupon the nipper starts to move rearwardly, the roller 13 riding down cam 23, until the jaws are closed 30 upon a fresh tuft of cotton which is fed forward in the usual way, and the needles have come around into operative position, as shown in Fig. 4, and the cycle of operations is complete.

It will be understood that the machine is 35 provided with an upper reciprocating comb (not shown) acting between the nipper and the detaching rolls, and with the other usual parts, all as fully described in said Nasmith 40 patent.

With the above described invention it is possible positively to control the path of the nipper jaws and their distance from the needles, by the positive control of the upper 45 nipper jaw, and to maintain such path either at a uniform distance at all points from the needles or at definite and predetermined graduated distances from the 50 points of the needles, notwithstanding the nipper as a whole is swinging in a circle of larger radius than that of a circle centered at the axis of the combing cylinder. Such positive control of the top nipper jaw also preserves the fixed and predetermined 55 distance between the lower edge of the top nipper jaw and the cylinder needles irrespective of the thickness of the cotton laps held by the jaws. By thus regulating the path of the nipper jaws relatively to the 60 needles, instead of following the arc of a circle centered at 4, it is possible to obtain deeper penetration of the tuft by the needles, and especially by the leading rows 65 of needles, and so cause them to do a larger share of the work of combing out the tuft,

thereby relieving the following and weaker needles and so reducing the breakage of the latter, and at the same time yielding a better product. Moreover, not only is an earlier and deeper penetration of the needles 70 effected, but just as complete penetration of the needles will be obtained when using a thick lap as when using a thin one, thus increasing the production of the machine by enabling it to use a heavier lap of cotton. 75 It is also possible to govern the distance between the nipper jaws and any of the rows of cylinder needles so as to obtain deeper penetration of some of the rows than of others. The use of a yielding lower jaw 80 or cushion plate in conjunction with the positively controlled upper jaw allows the lower jaw to accommodate itself to a lap of any desired thickness, and also to follow the positive movements of the upper jaw. 85

With this invention the nipper while closed and moving through its operative stroke over the comb cylinder, is guided in a predetermined path by means other than the nipper reciprocating means, which 90 means as herein exemplified consists of the swinging frame or arms 3, and consequently the nipper may follow a path other than the arc of a circle centered at 4, as contrasted with the machines heretofore made, in 95 which the path of the nipper was determined by the arc of a circle centered at the pivot of the nipper carrying arms or frame corresponding to the arms 3. Thus it is possible to govern the time of the deepest 100 penetration of the needles, and also the distance of the closed nipper from the needles at all points in its path, independently of the path of the reciprocating nipper carrying frame. Both jaws of the nipper are 105 movable on the nipper frame so as to be able to follow such predetermined independent path, and the cam surface 22, or equivalent means, for controlling the path of the nipper, preferably performs its guiding function by positively controlling the 110 upper nipper jaw, while the lower nipper jaw is yieldingly pressed against the upper jaw and so follows the path defined by the upper jaw. 115

I claim:

1. In a combing machine of the character described, a comb-cylinder, upper and lower nipper jaws, means to reciprocate the nipper jaws relatively to the comb-cylinder, a 120 nipper jaw guideway positively predetermined a fixed path for the upper jaw, and means permitting movement of the lower jaw with respect to the path of reciprocation for the upper jaw so fixed.

2. In a combing machine of the character described, a comb-cylinder, a nipper frame and means for imparting thereto a reciprocating motion, upper and lower nipper jaws both movably mounted on said nipper 130

frame, fixed means to move the upper jaw with respect to the frame to determine a fixed path therefor during the reciprocations of said frame, and means permitting the lower jaw to move with respect to the upper jaw.

3. In a combing machine of the character described, a comb-cylinder, a nipper frame pivoted to swing relatively to said comb-cylinder, means to reciprocate said frame, upper and lower nipper jaws both movably mounted on said frame, fixed means to guide the upper nipper jaw in a predetermined path other than the arc of a circle centered at the pivot of said frame, said lower jaw being yieldingly mounted to accommodate a variable thickness of sliver.

4. In a combing machine of the character described, a comb-cylinder, a nipper frame and means for imparting thereto a reciprocating motion, nipper jaws carried by said frame comprising an upper nipper jaw and a lower nipper jaw both movably mounted on said frame, a nipper guide positively controlling the path of movement of the upper nipper jaw, and means yieldingly urging the lower nipper jaw toward the upper jaw.

5. In a combing machine of the character described, a comb-cylinder, a nipper frame pivoted to swing relatively to said comb-cylinder, means to reciprocate said frame, nipper jaws carried by said frame comprising an upper nipper jaw movably mounted on said frame and a lower nipper jaw yieldingly urged toward said upper jaw, and means positively to guide the upper nipper jaw in a predetermined path.

6. In a combing machine of the character described, a comb-cylinder, a nipper frame and means for imparting thereto a reciprocating motion, nipper jaws carried by said frame comprising an upper nipper jaw and a lower nipper jaw both movably mounted

on said frame, a fixed cam guideway and a cam follower on said upper jaw adapted 45 positively to guide the upper nipper jaw in a predetermined path, and means yieldingly to urge said lower jaw toward the upper jaw.

7. In a combing machine of the character described, a comb-cylinder, a nipper frame pivoted to swing relatively to said comb-cylinder, means to reciprocate said frame, an upper nipper jaw, a pair of arms to which said upper nipper jaw is secured pivoted on said frame and having a cam follower, a lower nipper jaw pivoted on said frame, means yieldingly urging the lower jaw toward the upper jaw, and a cam on which said cam follower runs adapted to 55 control the path of the nipper jaws while in closed position.

8. In a combing machine of the character described, a comb-cylinder, a nipper frame pivoted to swing relatively to said comb-cylinder, means to reciprocate said frame, an upper nipper jaw, a pair of arms to which said upper nipper jaw is secured pivoted on said frame and having a cam follower, a lower nipper jaw pivoted on said frame, 65 means yieldingly urging the lower jaw toward the upper jaw, and a cam on which said cam follower runs adapted to control the path of the nipper jaws while in closed position, a second cam adapted to engage said 70 cam follower and open the upper nipper jaw, and means to limit the upward movement of the lower nipper jaw when the upper nipper jaw is withdrawn.

Signed by me at Boston, Massachusetts, 80 this 9th day of April 1915.

ARCHIBALD S. FULLER.
